US00D920021S

(12) **United States Design Patent** (10) **Patent No.:** **US D920,021 S**
Ben-Avi et al. (45) **Date of Patent:** **** May 25, 2021**

(54) **COMBINED COOLER AND TABLE**

(71) Applicant: **Keter Plastic Ltd.**, Herzliya (IL)

(72) Inventors: **Ehud Ben-Avi**, D.N. Emek Yizrael (IL); **Hadar Amiran**, Timrat (IL)

(73) Assignee: **Keter Plastic Ltd.**, Herzliya (IL)

(**) Term: **15 Years**

(21) Appl. No.: **29/700,359**

(22) Filed: **Aug. 1, 2019**

(30) **Foreign Application Priority Data**

Feb. 3, 2019 (IL) 63287

(51) **LOC (13) Cl.** **06-03**

(52) **U.S. Cl.**

USPC **D6/686**

(57) **CLAIM**

The ornamental design for a combined cooler and table, as shown and described.

DESCRIPTION

FIG. 1 is a top perspective view of a combined cooler and table, showing my new design in an open position;

FIG. 2 is a top perspective view, shown in a closed position;

FIG. 3 is a bottom perspective view, shown in an open position;

FIG. 4 is a bottom perspective view, shown in a closed position;

FIG. 5 is a front elevation view, shown in an open position;

FIG. 6 is a front elevation view, shown in a closed position;

FIG. 7 is a rear elevation view, shown in an open position;

FIG. 8 is a rear elevation view, shown in a closed position;

FIG. 9 is a right side elevation view, shown in an open position with the left side view being a mirror image thereof;

FIG. 10 is a right side elevation view, shown in a closed position with the left side view being a mirror image thereof;

FIG. 11 is a top plan view thereof; and,

FIG. 12 is a bottom plan view thereof.

1 Claim, 12 Drawing Sheets
